(57) **CLAIM**

The ornamental design for a television receiver with graphical user interface, as shown and described.

DESCRIPTION

FIG. 1 is a front view of a television receiver with graphical user interface showing our new design;

FIG. 2 is a front view of a second embodiment thereof; and, FIG. 3 is a front view of a third embodiment thereof.

The dashed broken lines showing the display screen are included for the purpose of illustrating environmental structure and form no part of the claimed design. The dash-dot broken lines define the bounds of the claimed design and form no part thereof.
